UNITED STATES PATENT OFFICE.

HENRI HÉBRARD, OF SCEAUX, FRANCE.

GYROSCOPIC TOY.

Application filed July 14, 1921. Serial No. 484,698.

To all whom it may concern:

Be it known that HENRI HÉBRARD, a citizen of the Republic of France, and resident of Sceaux, Seine, France (post-office address 54 Rue Voltaire), has invented new and useful Gyroscopic Toys, which improvements are fully set forth in the following specification.

My invention relates to a toy moving on two wheels and involves a novel application of the gyroscope, this device being utilized as a driving agent while ensuring, in the well known manner, the balance of the toy during the latter's travel.

15 The toy which is the object of my invention can assume many varied forms reminiscent of two-wheeled vehicles, as an example; my invention will be described hereinafter as applied to a scooter and a bicycle.

20 In order to make my invention more clearly understood I have appended hereto drawings wherein—

Figure 1 is a side elevation of a scooter built according to my invention;

25 Figure 2 is a bottom plan view of the same;

Figure 3 is a side elevation of a gyroscopic toy imitating the "torpedo-cycle," with part of the fuselage broken away to afford a view of the mechanism of the toy;

30 Figures 4 and 5 show various methods of using the toy;

Figure 6 is an embodiment of my invention as applied to a bicycle ridden by a cyclist whose legs follow the movements of the pedals.

In a gyroscopic toy built according to my invention, the gyroscope 1, of well known construction, is mounted in a vertical plane 40 on the frame C, in such a manner that its plane of gyration will be vertical when the toy is working. The shape of the frame is designed according to the kind of toy to be built. On the axle of the gyroscope a groove is provided into which engages an elastic cord 2 constituting a transmission and passing round the drive-wheel 3 of the toy; the diameter of the axle being much smaller than that of the wheel 3, there is obtained the reduction ratio required on account of the considerable speed of rotation on the gyroscope. The wheel 3 has its rim preferably fitted with a rubber band. The frame C comprises a part 4 intended to 45 guide the transmission cord 2 and to prevent it from contacting with the gyroscope.

rim which, without this provision, would have a braking action imposed on it by said cord and could not keep moving.

The fork 5 of the steering wheel 6 is 60 mounted loose in its support 7 so as to allow it to revolve freely in the said support during the working of the toy, such freedom of motion being necessary for balancing. It will be observed that, as shown by Figure 1, the fork 5 is reversed as compared with the position it usually occupies on a bicycle.

When my invention is applied to a scooter, as shown by Figure 1, the feet of 70 the dolls are fixed on the frame and its hands secured to a rod 8 simulating the steering rod of the toy.

In order to use the toy, it is merely necessary to set the gyroscope going, in the 75 well-known manner, by means of a string and to put down the toy on fairly smooth ground. The cord 2 transmits to the drive-wheel 3 the rotary motion of the gyroscope and the toy moves straight on, its stability 80 being ensured by the gyroscope.

The torpedo-cycle shown by Figure 3 is built in the same way, except for this sole difference that the frame is in the form of a fuselage 9 inside which the mechanism is 85 located, such fuselage being supposed to enclose the cyclist. The fuselage can be of open-work or skeleton character so as to permit access to the gyroscope for setting it going, or it can be entirely closed as 90 shown by Figure 3. In the latter case a window or any other suitable device has to be provided for setting the apparatus going.

As shown by Figure 4, the toy can be made to descend a track ending at its lower 95 portion in a vertical circle within which the toy runs, performing a "looping the loop."

Another method of using the toy consists in making it run around a mast as shown by Figure 5; for this purpose a small cord 100 is tied to one of the eyes 10 on the points between which the axle of the apparatus revolves, and over the mast is passed a loop made at the other end of the cord. The toy will then describe around the mast 105 circumferences having a radius equal to the length of the cord. The same result might be obtained by suspending a weight from one of the eyes 10.

The toy can be fitted with planes to appear as an "aviette" or flying push-bicycle. In the same order of ideas, the gyroscope

can be made to control, instead of the drive wheel 3, a tractor or propeller screw that will cause the toy to move on.

In the foregoing description, it has been specified that the gyroscope is used as a motor and this is an all important characteristic of my invention. My invention however, also contemplates a variation of the system according to which the motive power necessary to make the toy move on is supplied from or by another source (a spring clockwork, for instance which can be wound up and will set the gyroscope rotating).

As shown by Figure 6, the toy can be animated, i. e., for instance, in the case where the gyroscope is applied to a bicycle, the rider can be made to pedal exactly like a live cyclist riding a real bicycle.

It must be clearly understood that the bicycle is quoted only as an example, and that my present improvement will hold good as applied to any vehicle or apparatus in the shape of which the toy may be made.

As shown by Figure 6, the gyroscope located at *a*, carries at *a'* a small pulley around which passes an endless cable or cord *b* the displacement of which actuates a wheel *c* which constitutes the part that makes the rider's feet move thus playing the part of a crank pedal; said cord *b* also driving the rear wheel of the bicycle. The rider's legs, being articulated, have a pedalling motion imparted to them by the rotation of wheel *c*, while his body is rigidly fixed on the frame. Instead of passing around the rim of the rear wheel *d*, the cable *b* passes along a groove lateral to the wheel, an arrangement which allows the said wheel to remain in the plane of symmetry of the apparatus.

The front or steering wheel *e* is so mounted that its upper rod *f* can freely turn in the socket *g* secured on the frame.

The apparatus is set going, as in the preceding cases, by means of a string wound around the axle of the flywheel *a* and on which a rapid traction is exerted to impart impetus to the said flywheel.

The toy can move straight on or be made

to move along any curvilinear path. While moving, it is controlled and guided by means of a string tied at *h* on the rider's back. Due to this string the user can lead the toy; and as he can impart to it, for instance during turning, an impulsive motion, the toy, once wound up can work indefinitely, the winding up that keeps the gyroscope rotating being effected automatically by the user's intermittent pulls.

It must be understood, of course, that with this device as with the foregoing ones, the gyroscope can be set rotating either by a string or cord or by any mechanical means electrical or otherwise, whether amplifying or not.

Having now particularly described and ascertained the nature of my said invention and the manner in which the same is to be performed, what I claim is:

1. A gyroscopic toy, comprising a frame; front and rear wheels supported thereby and adapted to travel along a smooth supporting surface; a gyroscope mounted on the frame and having a driving connection leading from it to one wheel; and a figure mounted on said frame and having movable parts operatively associated with said driving connection to be actuated thereby.

2. A gyroscopic toy, comprising a frame; front and rear wheels supported thereby and adapted to travel along a smooth supporting surface; a gyroscope mounted on the frame and having a driving connection leading from it to one wheel; a figure embodying a fixed part rigidly secured to the frame and a part or parts movably related to the fixed part and operatively associated with said driving connection to be actuated thereby; and a flexible element connected to the fixed part of said figure to guide the toy and abruptly impel it during its travel so as to wind the gyroscope.

In testimony whereof I have signed this specification in the presence of a subscribing witness.

HENRI HÉBRARD.

Witness:

FERNAND DUFOUR.
